(57) **CLAIM**

The ornamental design for a display panel with animated graphical user interface as shown.

DESCRIPTION

FIG. 1 is a front view of a embodiment showing a display panel with animated graphical user interface design; FIG. 2 is a front view of a embodiment showing a display panel with animated graphical user interface design; FIG. 3 is a front view of a embodiment showing a display panel with animated graphical user interface design; FIG. 4 is a front view of a embodiment showing a display panel with animated graphical user interface design; FIG. 5 is a front view of a embodiment showing a display panel with animated graphical user interface design; FIG. 6 is a front view of a embodiment showing a display panel with animated graphical user interface design; FIG. 7 is a front view of a embodiment showing a display panel with animated graphical user interface design; FIG. 8 is a front view of a embodiment showing a display panel with animated graphical user interface design; FIG. 9 is a front view of a embodiment showing a display panel with animated graphical user interface design; FIG. 10 is a front view of a embodiment showing a display panel with animated graphical user interface design; FIG. 11 is a front view of a embodiment showing a display panel with animated graphical user interface design; FIG. 12 is a front view of a embodiment showing a display panel with animated graphical user interface design; FIG. 13 is a front view of a embodiment showing a display panel with animated graphical user interface design; FIG. 14 is a front view of a embodiment showing a display panel with animated graphical user interface design; FIG. 15 is a front view of a embodiment showing a display panel with animated graphical user interface design; FIG. 16 is a front view of a embodiment showing a display panel with animated graphical user interface design; FIG. 17 is a front view of a embodiment showing a display panel with animated graphical user interface design;

(Continued)

FIG. 18 is a front view of a embodiment showing a display panel with animated graphical user interface design; FIG. 19 is a front view of a embodiment showing a display panel with animated graphical user interface design; FIG. 20 is a front view of a embodiment showing a display panel with animated graphical user interface design; and, FIG. 21 is a front view of a embodiment showing a display panel with animated graphical user interface design.

The portions of the display panel with animated graphical user interface shown in broken lines illustrate portions of the display panel with animated graphical user interface that form no part of the claimed design.

1 Claim, 12 Drawing Sheets
